SPECTACLE HOLDER AND CONTAINER
COMBINATION

Jane C. Neiswanger, 500 19th St. NE,
Austin, Minn. 55912

Filed Oct. 23, 1965, Ser. No. 87,847

Term of patent 7 years

(Cl. D57—1)

FIG. 1

FIG. 4

FIG. 1 is a view in perspective of a spectacle holder and container combination, as seen from one side, the other side thereof being a mirror image;

FIG. 2 is a top plan view thereof;

FIG. 3 is a view in perspective thereof, as seen from the front; and

FIG. 4 is a view in perspective thereof, as seen from the rear.

The bottom not shown is substantially plain.

The broken line showing of the spectacles is for illustrative purposes only.

I claim:

The ornamental design for a spectacle holder and container combination, as shown and described.
